UNITED STATES PATENT OFFICE.

SAMUEL J. DUNKLEY, OF KALAMAZOO, MICHIGAN.

DESIGN FOR A BASKET-COVER.

SPECIFICATION forming part of Design No. 35,098, dated September 17, 1901.

Application filed May 20, 1901. Serial No. 61,193. Term of patent 3½ years.

To all whom it may concern:

Be it known that I, SAMUEL J. DUNKLEY, a citizen of the United States, residing at the city of Kalamazoo, in the county of Kalamazoo and State of Michigan, have invented a Design for a Basket-Cover, of which the following is a specification.

This invention relates to a design for a basket-cover.

10 The design is fully illustrated in the accompanying drawing, forming a part of this specification.

15 The figure is a perspective view of a basket-cover embodying the features of my design.

As shown in the drawing, the leading or material features of my design consist of

the band A and upwardly-looped cross-piece B and pieces C extending from the said band to substantially the center of the said cross-pieces. 20

Having thus described my invention, what I claim as new, and desire to secure by Letters Patent, is—

25 The design for a basket-cover, as herein shown and described.

In witness whereof I have hereunto set my hand and seal in the presence of two witnesses.

SAMUEL J. DUNKLEY. [L. S.]
